(57) **CLAIM**

The ornamental design for a lighter case, as shown and described.

DESCRIPTION

FIG. 1 is a top, front, right side isometric view of a lighter case showing my new design;

FIG. 2 is a top, front, left side isometric view of the lighter case of FIG. 1;

FIG. 3 is a top, rear, left side isometric view of the lighter case of FIG. 1;

FIG. 4 is a top, rear, right side isometric view of the lighter case of FIG. 1;

FIG. 5 is a bottom, front, right side isometric view of the lighter case of FIG. 1;

FIG. 6 is a bottom, front, left side isometric view of the lighter case of FIG. 1;

FIG. 7 is a left side elevation view of the lighter case of FIG. 1;

FIG. 8 is a right side elevation view of the lighter case of FIG. 1;

FIG. 9 is a rear side elevation view of the lighter case of FIG. 1;

FIG. 10 is a front side elevation view of the lighter case of FIG. 1;

FIG. 11 is top side elevation view of the lighter case of FIG. 1; and

FIG. 12 is a bottom side elevation view of the lighter case of FIG. 1; and,

FIG. 13 is a top, rear, left side isometric view of the lighter case of FIG. 1 in an open configuration.

The broken lines in the drawings depict portions of the lighter case that form no part of the claimed design.

1 Claim, 13 Drawing Sheets
